[57] **CLAIM**

The ornamental design for a sole for a shoe, substantially as shown and described.

DESCRIPTION

FIG. 1 is a bottom plan view of a sole for a shoe showing our new design;

FIG. 2 is a side elevational view of one side of the FIG. 1 sole;

FIG. 3 is a side elevational view of the other side of the FIG. 1 sole;

FIG. 4 is a front elevational view of the FIG. 1 sole;

FIG. 5 is a rear elevational view of the FIG. 1 sole;

FIG. 6 is a sectional view of the FIG. 1 sole, taken substantially as indicated by line 6—6 of FIG. 1;

FIG. 7 is a sectional view of the FIG. 1 sole, taken substantially as indicated by line 7—7 of FIG. 1; and

FIG. 8 is a sectional view of the FIG. 1 sole, taken substantially as indicated by line 8—8 of FIG. 2.
